US0D1011948S

(12) United States Design Patent (10) Patent No.: US D1,011,948 S
(45) Date of Patent:  Jan. 23, 2024

(54) JEWELRY ITEM WITH SPIKE PATTERN

(71) Applicant: Venus by Maria Tash, Inc., New York, NY (US)

(72) Inventor: Maria Tashjian, New York, NY (US)

(73) Assignee: Venus by Maria Tash, Inc., New York, NY (US)

() Term: 15 Years

(21) Appl. No.: 29/845,551

(22) Filed: Jul. 8, 2022

(51) LOC (14) Cl. 11-01

(52) U.S. Cl.

USPC D11/3

(58) Field of Classification Search

USPC D11/1-4, 40, 70

CPC A44C 7/00-002
